[57] **CLAIM**

The ornamental design for a clamp, as shown and described.

DESCRIPTION

FIG. 1 is a right side perspective view of a clamp showing my new design, the broken lines indicating environmental structure and forming no part of the claimed design;
FIG. 2 is a top plan view;
FIG. 3 is a front elevational view;
FIG. 4 is a left side elevational view, the right side being a mirror image thereof;
FIG. 5 is a rear elevational view; and,
FIG. 6 is a bottom plan view thereof.
